UNITED STATES PATENT OFFICE.

LEWIS D. PARKER, OF WEST HARTFORD, CONNECTICUT.

DESIGN FOR A MAT.

SPECIFICATION forming part of Design No. 29,459, dated October 4, 1898.

Application filed May 7, 1898. Serial No. 680,072. Term of patent 14 years.

To all whom it may concern:

Be it known that I, LEWIS D. PARKER, a citizen of the United States, and a resident of West Hartford, in the county of Hartford and State of Connecticut, have invented and produced a new and original Design for Mats, of which the following is a specification, reference being had to the accompanying drawings, forming part thereof.

10 Figure 1 is a plan view of the mat, showing my new design. Fig. 2 is an edge view of the same with one corner broken away to show a cross-section of the beveled edge.

As shown in the drawings, the leading or 15 material feature of my design consists in a band or border having a smooth surface extending around the ornamented portion, as shown, and beveled or sloping from said ornamented portion to the extreme edge of the 20 mat, which is comparatively thin. The central portion of the mat *a* is composed of ribs diagonally arranged with respect to each

other, forming depressions of diamond shape. These ribs and depressions are surrounded by a series of ribs and grooves extending 25 around the central portion, forming an edge *b* therefor. Outside of this edge *b* and extending around the mat is a plain smooth border or band *c*, beveled from the edge *b* to the edge of the mat, which is comparatively quite thin. 30 This beveled smooth band or border is of sufficient width to form a striking contrast when compared with the central portion of the mat, and serves to readily identify my design, thus forming the characteristic feature. 35

Having described my invention, what I claim as new, and desire to secure by Letters Patent, is—

The design for a mat substantially as herein shown and described.

LEWIS D. PARKER.
